United States Patent Office

Des. 196,467
Patented Oct. 1, 1963

196,467

MAIL BOX OR SIMILAR ARTICLE

John Mark Alley, 300 E. Sunnydell, Derby, Kans.

Filed Nov. 16, 1961, Ser. No. 67,554

Term of patent 7 years

(Cl. D74—9)

FIG. 1

FIG. 1 is a perspective view from the upper right front of a mail box showing my new design.

FIG. 2 is a perspective view of same from the lower rear left.

The essential features of the design reside in the portions shown in solid lines.

I claim:

The ornamental design for a mail box or similar article, as shown and described.
